US00D650349S

(12) **United States Design Patent**
Tom et al.

(10) **Patent No.:** **US D650,349 S**
(45) **Date of Patent:** ** *Dec. 13, 2011

(54) **HANDSET**

(75) Inventors: **Travis Tom**, Newbury Park, CA (US);
Boris Landwehr, Thousand Oaks, CA
(US)

(73) Assignee: **Nokia Corporation**, Espoo (FI)

(*) Notice: This patent is subject to a terminal disclaimer.

(**) Term: **14 Years**

(21) Appl. No.: **29/392,000**

(22) Filed: **May 16, 2011**
